UNITED STATES PATENT OFFICE.

WILLIAM H. FORSYTH, OF CHICAGO, ILLINOIS, ASSIGNOR TO THE
CURTAIN SUPPLY COMPANY, OF NEWARK, NEW JERSEY, A
CORPORATION OF NEW JERSEY.

CURTAIN FOR VESTIBULE-CARS.

No. 839,282.

Specification of Letters Patent.

Patented Dec. 25, 1906.

Application filed October 15, 1906. Serial No. 339,038.

To all whom it may concern:

Be it known that I, WILLIAM H. FORSYTH, a citizen of the United States, residing at Chicago, in the county of Cook and State of Illinois, have invented certain new and useful Improvements in Curtains for Vestibule-Cars, of which the following is a specification.

This invention relates to curtains of that type which are employed in connection with vestibule-cars and serve the purpose of covering the stanchions or door-posts of the intermediate arch-plates and bellows between the meeting ends of vestibule-cars, so as to protect the clothing and persons of passengers from injury while passing through the vestibule, and by covering the side walls of the passage-way also serve to decorate said passage-walls and give them a smooth and finished appearance.

A curtain of the type to which my invention relates is shown and fully described in Letters Patent to Thomas H. Wickes, No. 643,434, granted February 13, 1900, to which patent reference may be had for a complete disclosure of the parts and devices to which the present invention is applied as an improvement.

My invention is illustrated in practical forms in the accompanying drawings, in which—

Figure 1 is a cross-sectional view, broken out, of the adjacent portions of one side of the vestibules of two adjacent cars having my improvement applied thereto. Fig. 2 is a similar detail view illustrating the application of my invention to a yieldingly-held catch. Fig. 3 is a detail view, in vertical section, through the casing of the catch shown in Fig. 2; and Fig. 4 is a detail view on the line 4-4 of Fig. 1.

Referring to the drawings, and first briefly describing the main parts of the device to which my improvement is applied, 10 may indicate the stanchions forming the door posts or jambs of the end doorway of the vestibule, and 11 may indicate the usual contacting arch-plates disposed therebetween.

12 indicates in broken section the bellows which connect the respective arch-plates to the stanchions. In each vestibule, at one side thereof, is mounted vertically a roller 13, controlled by a spring 14 in the manner usual

and well known in spring-rollers for window-curtains and the like, this roller being herein shown as mounted in a cylindrical metal case 15, which is supported by one or more brackets 16 and is provided with a longitudinal slot 17, through which the curtain 18 passes, one end of said curtain being suitably secured to the spring-actuated roller 13, as will be readily understood. The free end of the curtain or screen is provided, as usual, with a stock or rod 19 to stiffen and strengthen the same and with a loop-shaped handle 20, secured to said rod, by means of which the curtain or screen is readily grasped and moved back and forth.

21 in Figs. 1 and 4 represents a catch secured to the outer face of the stanchion 10, as by means of screws 22, passed through its base-plate 23. This catch has heretofore been made solid and of a form to frictionally engage the loop-shaped handle 20 when the latter is passed thereover. It has been found in practice that owing to the almost continuous vertical vibration of the adjacent ends of the vestibule when the train is in motion and the consequent relative rising and falling movements of the handle and catch great friction and rubbing is produced between said handle and catch, which wears away the metal of both parts and renders them short-lived and soon liable to break. To improve the condition and wearing qualities of these parts in accordance with my present invention, I provide them with an antifriction device between their contacting or rubbing surfaces. Preferably and as herein shown this antifriction device is applied to the catch 20 and may take the form of a peripherally-grooved roller 24, that may be rotatably mounted on a pin 25 in a slot 26, formed in the catch. The grooved periphery of the roller 24 engages the handle 20, and the rising and falling movements of the handle simply turn the roller back and forth on its bearing, and thus eliminate frictional rub and wear between the handle and the catch. When these parts are thus equipped, their durability and longevity are greatly increased, and they will wear almost indefinitely. In some forms of this class of curtains the catch has been made elastically yielding or retractile by backing the catch with a spring of greater strength than the curtain-roller spring, but

capable of yielding and permitting a separation of the handle from the catch under unusual strains or when through carelessness or accident the cars are separated without having first released the curtain from the catch. Such a retractible catch is illustrated in the Letters Patent No. 643,434, hereinabove referred to, and in Figs. 2 and 3 I have illustrated the application of my invention to a catch of this type. Referring to said figures, 27 designates the catch, the same being mounted rotatably on a vertical pin 28 in a metallic socket-piece 29, sunk in and secured to the stanchions 10. Said socket-piece has formed in its outer wall a transverse slot 30, through which the catch is capable of swinging backwardly sufficiently to release the handle under unusual or accidental strain. One or more torsion-springs 31, surrounding the pivot-pin 28 and bearing at one end against a catch and at the other end against the casing, normally project the catch forwardly with a strength exceeding that of the curtain-roller spring. The catch 27 is in accordance with my invention provided with a forwardly-projecting pintle or spindle 32, on which is rotatably mounted a peripherally-grooved antifriction-roller 33, adapted to engage the loop-shaped handle 20 in the manner clearly shown in Fig. 2. It will be evident that the roller 33 in this form or application of the invention performs the same function and purpose in the same manner as in the rigid or non-yielding form shown in Figs. 1 and 4.

It will be evident from the foregoing that my invention provides a simple and efficient means of obviating the severe and extensive wear and deterioration that has hitherto ex-

isted between the handle and the catch in this class of devices. Believing myself to be the first to provide an antifriction means between these parts in a device of this character, I do not limit the invention to the particular forms of antifriction devices herein shown or to the particular use to which the curtain is applied.

I claim—

1. The combination with a spring-actuated curtain having a handle, and a catch, of antifriction means between said handle and catch.
2. The combination with a spring-actuated curtain having a handle, and a catch, of an antifriction-roller between said handle and catch.
3. The combination with a spring-actuated curtain having a handle, and a catch, of an antifriction-roller mounted in said catch and adapted to engage said handle.
4. The combination, with the vestibuled ends of each of two adjacent cars, of a vertical spring-actuated roller mounted in one of said ends adjacent to the passage-way between said vestibuled ends, a curtain or flexible screen connected to said roller and adapted to be laterally extended along the side walls of said passage-way, a loop-shaped handle connected to the free end of said curtain or screen, a catch secured to the opposite vestibuled end of the adjacent car, and an antifriction device carried by said catch and engaging said handle.

WILLIAM H. FORSYTH.
